United States Patent Office.

GEORGE WILKINSON, OF PROVIDENCE, RHODE ISLAND, ASSIGNOR TO GORHAM MANUFACTURING COMPANY, OF SAME PLACE.

Design No. 3,817, dated January 11, 1870.

DESIGN FOR AN EGG-CUP AND SALT-STAND.

The Schedule referred to in these Letters Patent and making part of the same

To all whom it may concern:

Be it known that I, GEORGE WILKINSON, of the city and county of Providence, and State of Rhode Island, have originated a new Design in articles of silver and plated ware, for Salt-Stands and Egg-Cups, of which the accompanying photograph, with this specification, is a complete description thereof, that is to say, the articles of salt-stands and egg-cups, substantially as shown in the said photograph.

Claim.

The design for salt-stands and egg-cups, substantially as herein set forth.

GEO. WILKINSON.

Witnesses:

J. F. P. LAWTON,
S. A. BARTON.
